CLAIM

The ornamental design for garlic-squeezer, as shown and described.

DESCRIPTION

FIG. 1 is a perspective view of the garlic-squeezer showing my new design;
FIG. 2 is a bottom plan view thereof;
FIG. 3 is a right side elevational view thereof;
FIG. 4 is a front elevational view thereof;
FIG. 5 is a rear elevational view thereof; the left side view is a mirror image of the right side view illustrated in FIG. 3.
